BELT BUCKLE

Roland Beuchat and Samuel Junod, Geneva, Switzerland

Application March 6, 1953, Serial No. 340,755

4 Claims. (Cl. 24—178)

Our invention has for its object a connecting unit including a buckle and a pivoting catch thereon, said unit being intended for use with a yielding belt or the like perforated yielding fastening member.

According to a main object of our invention, a cross-member of the buckle located at a distance from the pivotal axis of the catch carries a spring the ends of which are held by said cross-member while the medial part of said spring forms a collapsible bearing for the tip of the catch, said spring being provided with control parts operable from the outside of the cross-member and that are designed in a manner such that the user exerting a pressure on said control parts produces an elastic deformation of the spring and consequently a receding movement of the medial part thereof away from the path of the tip of the catch, which allows the latter to move from one side of the cross-member to the other and to drop thus out of the perforation of the belt or the like fastening member engaged by said catch as soon as a mere pull is exerted on the buckle.

Our invention relates in particular to an embodiment of such a buckle wherein the cross-member assumes the shape of a flat tube serving as a carrier for the spring and as a guide for its deformations which are limited in practice to a plane. Said flat tubular cross-member is provided with a medial notch in its wall facing the catch to allow the passage of the tip of the catch therethrough when released.

We have illustrated by way of example in accompanying drawings a preferred embodiment of our improved buckle associated with a fastening member. In said drawings:

Fig. 1 illustrates in plan view the ends of a belt provided with a buckle carrying a pivoting catch.

Fig. 2 is a perspective view of the buckle shown alone without the belt.

Fig. 3 is a plan view partly sectional of the buckle showing the abutment provided for the catch on the spring.

Fig. 4 is a plan view of the same buckle, the abutment on the spring lying in its catch-releasing position.

As illustrated in Fig. 1, one of the ends of the belt L is secured as known per se to a cross-member or bar 2 of a buckle generally designated by the reference letter B.

The bar 2 forms a pivot for the catch 3 engaging a perforation 4 in the belt L. The buckle B, assuming the shape of a generally rectangular frame, includes in addition to said bar 2 two parallel lateral members 5 and a second cross-member 6 facing the bar 2.

Said second cross-member 6 is constituted by a thin-walled preferably flat tube provided with a notch 7 in the middle of its wall facing the catch for the passage therethrough of the tip 3' of the catch 3.

A spring constituted by a wire 8 assuming a circular cross-section is fitted through its ends 9 and 10 between the inner terminal parts 11 of the lateral members 5 of the buckle, registering with the outer ends of the tube 6. These terminal parts 11 of the lateral members are pro-

2

vided each with an elongated opening 12 through which the corresponding end of the spring 8 projects, said end being bent into arcuate shape as shown respectively at 13 and 14. Starting from the arcuate end 13 of the spring towards the middle of the tube, the spring 8 includes a slightly incurved section 15 followed by two sharp bends 16 and 17 facing opposite directions and merging into the medial section 18 which normally crosses the notch 7 in the tube.

Similarly, the spring includes between its opposite arcuate end 14 and the medial section 18 a comparatively long slightly incurved section 19 followed by two sharp bends 20 and 21 arranged symmetrically with reference to the bends 16 and 17 with reference to a medial plane A—A forming the longitudinal plane of symmetry of the buckle that is perpendicular to the plane of Fig. 3. The symmetrical bends 16 and 20 engage each other at least when the spring is in the catch-supporting position of Fig. 3. Each of the end sections 13, 14 of the spring carries a rounded control part 22 or 23 passing through the corresponding elongated opening 12 in the lateral members.

The above-described buckle associated with the belt L may be used in the following manner:

When the belt is to remain fastened, the tip 3' of the catch engages the medial part 18 of the spring 8, said tip 3' being guided laterally by the edges of the notch 7.

When it is desired to unfasten the belt L, the user urges simultaneously the two control parts 22, 23 inwardly by exerting a pressure with two fingers in the directions of the arrows F1 and F2 in Figure 4. This produces a lateral flexion of the spring 8 which assumes a bent position as shown in interrupted lines in Fig. 4. By reason of the deformation of the spring 8, its medial part 18 is shifted in the direction of the arrow F3 and frees thus completely the notch 7 formed in the tubular cross-member 6. At this moment, and while he continues exerting a pressure on the control parts 22—23, the user need only draw the buckle in the direction of the arrow F4 of Fig. 1 to shift the catch 3 from the upper surface of the buckle B towards its lower surface so as to assume the position illustrated in dot and dash lines at 3a in Fig. 2. When this position is reached, the tip 3' of the catch disengages automatically the perforation 4 in the belt which is thus unfastened. During its deformation, the spring 8 is guided substantially in a plane inside the flat tube 6 between the parallel upper and lower surfaces of the flat tube 6.

What we claim is:

1. A buckle for belts and the like yielding perforated fastening members comprising a quadrangular structure including a cross-member for attachment of a belt thereto, two side members and a tubular cross-member, a catch pivotally secured to the first cross-member and adapted to project through a perforation of the belt, into register with the medial portion of said cross-member, said catch being adapted to pivot freely between an operative position on the outer side of the second cross-member and an inoperative position on the inner side of said second cross-member for which latter position a mere drawing of the buckle in a direction extending from the first cross-member towards the second cross-member releases the catch from the perforation in the belt, a spring extending longitudinally inside the tubular cross-member, said spring including a medial part adapted to be engaged by the tip of the catch in its operative position, two terminal sections forming curves of small radii projecting outside the buckle and forming finger-operable control sections, two elongated slightly incurved sections forming inward extensions of the terminal control sections, two pairs of sections assuming the shape of sharp bends in opposite directions and con-

necting each a slightly incurved section with the medial section, the spring when submitted to compression between its control sections assuming a flexional bend constraining the medial section to recede and to release the tip of the catch.

2. A buckle for belts and the like yielding perforated fastening members comprising a quadrangular structure including a cross-member for attachment of a belt thereto, two side members and a flat tubular cross-member, a catch pivotally secured to the first cross-member and adapted to project through a perforation of the belt, into register with the medial portion of said cross-member, said catch being adapted to pivot freely between an operative position on the outer side of the second cross-member and an inoperative position on the inner side of said second cross-member for which latter position a mere drawing of the buckle in a direction extending from the first cross-member towards the second cross-member releases the catch from the perforation in the belt, a spring extending longitudinally inside the flat tubular cross-member, said spring including a medial part adapted to be engaged by the tip of the catch in its operative position, two terminal sections forming curves of small radii projecting outside the buckle and forming finger-operable control sections, two elongated slightly incurved sections forming inward extensions of the terminal control sections, two pairs of sections assuming the shape of sharp bends in opposite directions and connecting each a slightly incurved section with the medial section, the spring, when submitted to compression between its control sections assuming a flexional bend constraining the medial section to recede and to release the tip of the catch, the first sharply bent sections connected directly with the slightly incurved sections on each side of the medial section engaging each other elastically when the spring is not submitted to compression.

3. A buckle for belts and the like yielding perforated fastening members comprising a quadrangular structure including a cross-member for attachment of a belt thereto, two side members and a flat tubular cross-member provided in its medial part with a notch facing the first mentioned cross-member and opening into the inside of the tubular cross-member, a catch pivotally secured to the first cross-member and adapted to project through a perforation of the belt registering with said notch, said catch including a tip adapted to enter the tubular cross-member through said notch to pivot freely between an operative position on the outer side of the second cross-member and an inoperative position on the inner side of said second cross-member for which latter position a mere drawing of the buckle in a direction extending from the first cross-member towards the second cross-member releases the catch from the perforation in

the belt, a spring extending longitudinally inside the flat tubular cross-member, said spring including a medial part facing the notch and adapted to be engaged by the tip of the catch in its operative position, two terminal sections forming curves of small radii projecting outside the buckle and forming finger-operable control sections, two elongated slightly incurved sections forming inward extensions of the terminal control sections, two pairs of sections assuming the shape of sharp bends in opposite directions and connecting each a slightly incurved section with the medial section, the spring when submitted to compression between its control sections assuming a flexional bend constraining the medial section to recede and to release the tip of the catch.

4. A buckle for belts and the like yielding perforated fastening members, comprising a quadrangular structure including a first cross-member for attachment of an end portion of a belt thereto, two side portions and a second cross-member provided with a notch at its medial part, said notch facing said first cross-member, a catch pivotally secured to the first cross-member and adapted to project through a perforation of the belt, into register with said notch, said catch including a tip adapted to pass through said notch to pivot freely between an operative position on the outer side of said second cross-member and an inoperative position on the inner side of said second cross-member for which latter position a mere drawing of the buckle in a direction extending from the first cross-member towards the second cross-member releases the catch from the perforation in the belt, a spring longitudinally fitted on said second cross-member, said spring including a medial part registering with said notch and adapted to be engaged by the tip of the catch in its operative position, two terminal sections shaped as curves of small radii projecting outside the buckle and forming finger-operable control sections, said terminal sections comprising end portions adapted to engage under pressure in opposite directions the inside of said side members of the buckle, two elongated slightly incurved sections forming inward extensions of the terminal control sections, two pairs of sections assuming the shape of sharp bends in opposite directions and connecting each a said slightly incurved section with the medial part, the spring when submitted to compression between the control sections assuming a flexional bend constraining the medial part to recede away from said notch and to release the tip of the catch.
